WHEEL TRIM UNIT

Charles B. Aske, Jr., Birmingham, and Edward L. Wood,
Detroit, Mich.

Application April 4, 1958, Serial No. 50,338

Term of patent 14 years

(Cl. D14—30)

FIG. 3

Fig. 1 is a side elevational view of a wheel trim unit embodying the new design; and

Fig. 2 is a sectional view taken on the line 2—2 of Fig. 1; and

Fig. 3 is a view in perspective.

The dot and dash line showing of a vehicle wheel and tire in Fig. 1 is for the purpose of illustration only.

This application is a continuation-in-part of application Serial No. D. 47,970 filed by Edward L. Wood on October 4, 1957.

We claim:

The ornamental design for a wheel trim unit as shown and described.
